APPARATUS FOR TESTING WATER MAINS

Filed May 3, 1924

UNITED STATES PATENT OFFICE.

JOHN A. COLE, OF CHICAGO, ILLINOIS.

APPARATUS FOR TESTING WATER MAINS.

Application filed May 3, 1924. Serial No. 710,843.

To all whom it may concern:

Be it known that I, JOHN A. COLE, a citizen of the United States, residing at Chicago, in the county of Cook and State 5 of Illinois, have invented certain new and useful Improvements in Apparatus for Testing Water Mains; and I do hereby declare the following to be a full, clear, and exact description of the invention, such as 10 will enable others skilled in the art to which it appertains to make and use the same.

My invention relates to new and useful improvements in apparatus for making velocity tests in city water mains, and consists 15 of an improved means for employing the broad idea of the measuring instrument disclosed in my prior Letters Patent No. 1,485, 831, of March 4, 1924.

In the use of the aforesaid patent and 20 other devices of the kind, it is necessary to have the manhole uncovered for a prolonged period of time while a test is being made.

At the present time, with the rapidly increasing use of automobiles in the cities and 25 the congested condition of traffic, it is very dangerous, not only to the travel, but to the persons making a water test, to have to remain in the street with the manhole un- 30 covered.

To this end, I have provided an apparatus, which will enable the tests to be made from a sidewalk, vault or manhole, the street manhole being opened only for a short pe- 35 riod while the device is being attached to the water main.

Another object of my invention is to provide means for preventing the freezing of the water in the tubes of the device, in cold 40 weather.

With the above and other objects in view which will appear as the description pro- 45 ceeds, my invention consists in the novel features herein set forth, illustrated in the accompanying drawing and more particu- 50 larly pointed out in the appended claims.

In the drawings numerals of like char- 55 acter designate similar parts throughout the several views, and—

Fig. 1 is a sectional view of the two man- 60 holes, showing the complete apparatus.

Fig. 2 is an enlarged sectional view taken on line 2—2 of Fig. 1.

Fig. 3 is a sectional view of the water 65 main and the valve for inserting the "Pitot tubes."

Fig. 4 is a detail view of the mechanism for taking up the slack in the rubber tubing after the device is connected up, and

Fig. 5 is a detail view of the pressure 60 tubes and casing.

1 designates the wall of an ordinary street manhole, through the lower portion of which extends a water main 2. At 3 I have shown a supplemental manhole situated under the side walk and of about one-half the size of the street manhole.

These two manholes are connected by means of an inclined conduit or pipe 4, which serves as an outer casing for the pres- 70 sure conveying tubes 5, said tubes being preferably composed of brass and enclosed in a casing 6 longitudinally slidable in the outer casing 4 and preferably of wood or metal made in two parts and secured together by 75 screws 7, as shown in cross section in Fig. 2.

The brass tubes 5 extend slightly beyond the ends of the casing 6, and are adapted to receive pliable rubber connecting tubes 8 and 9 which are secured thereto by means 80 of wires or clamps 5^a in the manner shown in Fig. 5.

The free ends of the rubber tubes 8, are placed over the tubes 10 of the meter 11 of the usual form of Pitot tube rod meter, 85 which is connected to the water main 2, in such a manner that when the device is in operation the L's 10^a of the Pitot tubes 10 will project in opposite directions along the center of the water main. 90

The operation of attaching the rubber tubes 8 to the meter in the street manhole requires much care, and calls for a length of rubber tubing considerably longer than can be kept in use after the meter has been 95 lowered to the center of the water main. This excess of rubber tubing, unless disposed of, will block the action of the meter by creating pockets where air will accumulate. The vertical space between the top of 100 the meter 11, and the inclined tubes 5 is quite restricted and the rubber connections must be direct.

To this end I provide the means, shown in Fig. 4, for taking up the slack rubber 105 tubing, which consists of an inwardly projecting support 12, secured to the wall of the manhole by spikes or any other suitable means. Pivoted to this support is a bell crank lever 13 including two arms 14 and 15, the latter being pivotally secured to a connecting rod 16, which in turn is pivoted 110

at 17 to the tube casing 6. The arm 14 of the lever 13 is adapted to serve as a handle by means of which the casing and tubes 5 may be drawn outwardly from the conduit 5 or outer casing 4, or pushed inwardly therein. By so operating the handle 14, the rubber tubes are rendered taut or loose as desired.

After the tubes 8 are in the desired position, the rubber tubes 9 at the other end of the casing 6, are connected to the indicating instrument 19 and the apparatus is ready for a test.

The brass tubes 5 and the casing 6 may be made in sections and joined together, and in order to enable the inspection of these joints, I provide narrow chambers 16 in the walls of the manholes 1 and 3 on a line with the casing 6, into which said casing may be extended.

In sections of the country which suffer from severe winters, it may be advantageous to provide heat to prevent the apparatus from freezing.

To this end I employ electric coils 18 in the casing 4 which will heat that portion of the device through which a fine stream of water must pass. If desired, other heating means may be employed in the manholes, but in most cases this is not believed to be necessary.

The operation of my device is obvious. The person making the test enters the street manhole 1 only long enough to attach the rubber tubes 8 to the meter 11, open the valve on the meter and lower the Pitot tubes to the center of the main; then by means of the handle 14 he forces the casing 6 longitudinally into the conduit 4, thus taking up any slack in the rubber tubes.

He then connects the rubber tubes 9 to the indicating instrument 19 in the side walk manhole 3, and covers the street manhole and finishes his test from the side walk manhole.

From the foregoing, it is believed that my invention may be clearly understood without further description, and in closing

it may be stated that numerous changes may be made in the details of construction without departing from the spirit of the invention as disclosed in the following claims.

What I claim and desire to secure by Letters Patent is:—

1. Means for testing a water main extending under a street, including a street manhole, a side walk manhole, a meter arranged in the street manhole, extending into the water main and actuated by the water flowing through the main, an indicating instrument arranged in the side walk manhole, and means operatively connecting the meter to the indicating instrument, whereby the velocity of the water flowing through the main will be indicated by the instrument in the side walk manhole. 55 60 65

2. Means for testing a water main extending under a street, including a street manhole, a side walk manhole, a conduit connecting said manholes, tubes extending through said conduit, a meter in said street manhole and an indicating device in said side walk manhole, and means for connecting said tubes to said meter and said indicating device. 70 75

3. Means for testing a water main extending under a street, including a street manhole, a side walk manhole, an inclined conduit connecting said manholes, tubes extending through said conduit, a casing for said tubes, a meter in said street manhole and an indicating device in said side walk manhole, flexible connections for connecting said tubes to said meter and indicating device, and mechanism for taking up any slack in said flexible connections. 80 85

4. Means as claimed in claim 3 wherein the mechanism for taking up the slack in said connections, consists of a support secured to the wall of said street manhole, a bell crank lever pivoted to said support, a rod pivoted to said lever at one end and to said tube casing at the other end. 90

In testimony whereof I affix my signature.

JOHN A. COLE.
